BRASSIÈRE SLIP

Harold Roth, New York, N. Y.

Application March 3, 1952, Serial No. 274,555

3 Claims. (Cl. 2—73)

1

The present invention relates to a brassière slip combination and although it will be specifically described in connection with its application to a brassière slip, it is to be understood that it also has application to a brassière construction by itself without the attached skirt.

It is among the objects of the present invention to provide a simple, readily manufactured, well-fitting brassière slip or brassière combination of the strapless type which will closely hug the figure without drooping, and which will fit a wide variety of breast sizes and accommodate itself to various waist heights.

Another object is to provide a brassière slip or a brassière of the strapless type in which the supports will be most conveniently positioned centrally at the front of the combination to give assurance that the brassière or brassière slip as the case may be will closely fit the breast without falling and without distortion of the outside dress and with further assurance that the strapless brassière or brassière slip may be used either as an inner or outer garment, as the case may be.

Another object is to provide a strapless brassière or brassière slip which will closely conform to the figure and which may carry rigid supports without the ends of said supports digging into the body or causing distortion of the external covering garment.

Still further objects and advantages will appear in the more detailed description set forth below, it being understood, however, that this more detailed description is given by way of illustration and explanation only and not by way of limitation, since various changes therein may be made by those skilled in the art without departing from the scope and spirit of the present invention.

According to the preferred embodiment of the present invention, there is provided a strapless brassière or brassière slip having a plurality of vertical elastic panels at the front or sides thereof, or both, which will extend substantially from the top of the brassière or brassière slip to the waistline.

These vertical elastic panels may all be positioned at the side of the garment or they may be positioned partly at the side of the garment and partly in front of the garment. The breast-covering sections are desirably made in two sections, one extending over the top and inside faces and having its bias extending longitudinally off the maximum diameter, and the other extending across the lower outside portions of the breast cup

2

with its bias substantially at right angles to the bias of the single piece.

The breast covering sections are desirably separated by one or two vertical panels which extend from the waistline substantially to the top of the garment, and which desirably consist of two pieces joined together at the front of the garment. The front of the garment is preferably provided with a deep cleavage carrying pockets at the sides and base of the cleavage for receiving a V or U shaped wire support. Although additional supporting bones or rods may be employed it is sufficient for many purposes merely to use the V shaped wire member by itself.

With the foregoing and other objects in view, the invention consists of the novel construction, combination and arrangement of parts as herein-after more specifically described, and illustrated in the accompanying drawings, wherein is shown an embodiment of the invention, but it is to be understood that changes, variations and modifications can be resorted to which fall within the scope of the claims hereunto appended.

In the drawings wherein like reference characters denote corresponding parts throughout the several views:

Fig. 1 is a front perspective view of the upper portion of a strapless brassière or brassière slip.

Fig. 2 is an inside fragmentary elevational view of the central front inside portion of the garment of Fig. 1 showing only part of the breast pocket construction.

Fig. 3 is a front elevational view of the central support V shaped wire removed from the pocket and enclosure of Fig. 2.

Fig. 4 is a transverse fragmentary vertical sectional view upon the line 4—4 of Fig. 2 upon an enlarged scale as compared to Fig. 2.

Fig. 5 is a horizontal transverse sectional view upon the line 5—5 of Fig. 2 upon an enlarged scale as compared to Fig. 2.

Referring to Fig. 1 there is shown a brassière top A which as shown is provided with a skirt B. The brassière may be a separate article without attached skirt if desired. The brassière slip, as shown in Figs. 1 and 2, may have elastic side sections C and also if desired elastic central sections D and breast covering sections E. There is a deep cleavage as indicated at F extending downwardly along the central sections D.

Alongside of this cleavage and supporting the same is the V shaped or U shaped frame member G. The upper breast covering sections 10 extend over the top and inside faces of the breast. The bias of this section extends in the manner indicated by the double headed arrow 11.

These sections are finished at the top by the ruffles 12 and at their outside edges 13 they are connected to the upper portion 14 of one of the side elastic panels 15.

As shown in Fig. 1 there are three side elastic panels 15, 16 and 17 joined together to the stitching 18 and 19, but if desired one or more of these panels may be of non-elastic fabric. These panels are joined at the waistline H to the upper edge 20 of the skirt B. The inside edge 21 of the panels 18 is joined by the stitching 22 to the square sections 23 which have a bias as indicated at 24. The line of stitching 22 extends around the lower outside face of the breast cup at a point below the maximum projection thereof.

The lower edges 25 and 26 of the sections 23 and 19 are joined by the double stitching 28 to the top 27, of the panel 29. The panel 29 at its outside edge 30 is shown at the vertical section 15 and at its bottom edge 31 is stitched at 32 at the waistline H to the top of the skirt B.

The bias of the sections 29 extends diagonally as indicated at 33, and these sections 29 cover the front of the body below the breast cup down to the waistline H.

The inside or central edge 50 of the sections 16 is stitched at 51 to the pocket construction 52, which may receive a stiffening rod or bone, as the case may be. The pocket 52 at its inside or central edge may be provided with a single or double layer of elastic material to receive the legs 54 of the V-shaped or U-shaped wire element or vertical stiffening support G. As shown best in Fig. 5 there may be a single or double layer of elastic fabric 53 between which may be positioned a stiffening leg 54.

As shown best in Figs. 2 and 4, the inside ply 53 terminates at 55 so as to form a position for upward insertion, as indicated by the arrows 56, for the top ends 57 of the legs 54 of the V- or U-shaped wire G. The top ends of the wire 54 are bent downwardly and inwardly as indicated at 59 so that they will slide readily upwardly through the pocket formed by the plies 53 and through the space 60 indicated in Fig. 5. These two plies are turned inwardly at their inside ends, as indicated at 63, and stitched at 61 to the shirring edging 62 which constitutes an extension of the top shirring 12.

The plies 52 at their outside edge will extend to the position 63 and they will be stitched at 64 to the front and rear plies of the various panels which make up the pockets 52. As shown in Fig. 5, the panel 19 may consist of two plies one of which terminates at 65 and the other of which is bent backwardly at 66 to terminate at 67 (see Fig. 5).

The rear or inside face of the pocket may consist of a main ply 68 with an inside reinforced ply 69. The rear ply 68 is turned inwardly at 70 and 71 with the inside edges overlapping as indicated at 72.

The stitching 64 stitched at 73 will hold the various sections of fabric together in and about the pocket as shown in Fig. 5. The reinforcing bone 74 may be inserted between the ply 68 and the over-lapped inside ply 72. The front of the garment will be indicated by the arrow 75.

Although the construction may widely vary, the plies 76, 77, 78 and 79 may be of nylon or cotton. The plies 80 may be of leno or elastic cloth.

The ply 69 may be of heavy cotton braid stitched to the tubular member 68 to resist the edges of the bone 76. The tubular member 68 together with its folded edges 70 and 71 and the 75

over-lapping portions 72 may be of jean cotton.

Referring to Fig. 2, it will be noted that the cleavage indicated by F terminates at 90 and below 90 there extends the panel 91 down to the waistline between the side panels 53. The panel 91 is attached at 92 to the skirt B at the waistline H. Stitched across the panels 53, 91 and the edges of the rear tubular panels 68 is the pocket member 93. The pocket member 93 forms a receptacle for the bottom or base 94 of the V-shaped wire G.

As shown in Fig. 2 the V-shaped wire G may be readily inserted in the pockets formed between the plies 53 and through the open lower edge 55 in the manner indicated by the arrows 56. Then, if the legs 54 are forced upwardly, the bottom loop or base 94 may be inserted into the pocket 93.

The V-shaped member G will then drop down and be retained firmly in position by engagement of the loop 94 in the pocket 93 and by the legs 54 engaged in the pockets 59 (see Fig. 5).

The invention will achieve a firm support of a relatively deep cleavage strapless brassière or brassière slip garment with or without the addition of the bone 74. The garment will be self supporting, will not be uncomfortable and will not tend either to cut into the skin or body of the wearer nor into the outer covering garment.

The structure as shown in Figs. 1 and 2 may in itself be used as an outer garment in which case the panels 16, 15, 16, 17, 23, 29, 52, 53 and 91 may be made of an outside dress fabric or may be provided with a facing of an outside dress fabric.

The cut of the panels 19 around the upper portion and inside face of the breast pocket and of the short panel 23 at the lower outside face of the breast pocket will assure substantially automatic conformation to the body contour.

The thin vertical panels 15, 16, 17, 53 and 91 also enhance the fit of the garment particularly where these sections altogether or in alternation are made of elastic material such as leno.

The multi-ply pocket construction 52 will enhance the uprightness and self support features of the garment even without insertion of the bone 74.

As many changes could be made in the above brassière slip, and many widely different embodiments of this invention could be made without departing from the scope of the claims, it is intended that all matter contained in the above description shall be interpreted as illustrative and not in a limiting sense.

Having now particularly described and ascertained the nature of the invention, and in what manner the same is to be performed, what is claimed is:

1. In a brassière top slip garment, the brassière portion of which is provided with separated breast cups and a deep plunging neckline between said breast cups, said breast cups each consisting of two fabric sections, the top section forming the top and inside portion of the breast cups, and the lower section forming the lower outside portion of the breast cups, said sections being joined together by a seam extending in a curved line from the outside edge of the breast cups across the center of the breast cups to the lower edge of the breast cups and a V-shaped pocket structure stitched to the inside edges of the top section of the breast cups and extending vertically between the breast cups and serving together with its folded edges 70 and 71 and the 75 to connect said breast cups and a V-shaped stiff-

fening member position in and retained by said pocket structure.

2. The garment of claim 1, there being provided two elongated pockets extending along the inside edges of each breast cup to substantially below the breast cups for holding the upper ends of the legs of the V-shaped stiffening member and a lower pocket member substantially below the breast cups for receiving the bottom of the V of said stiffening member, said pocket structure including elongated strips of farbic material stitched to the inside edges of the breast cups and extending substantially below the breast cups to the waistline of the garment.

3. The garment of claim 1, said top section 15 having a bias extending from the outside edge of the breast cups to the lower edge of the breast

cups and parallel to the curved seam and said lower section having a bias extending transversely to the bias of the top section and there being fabric sections extending from the lower edge of the breast cups to the waistline of the garment.
